UNITED STATES PATENT OFFICE.

WILLIAM A. WEAVER AND WILLIAM T. BROWN, OF COVENTRY, ENGLAND.

ROLLER-STEADY FOR LATHES.

1,181,495.

Specification of Letters Patent.

Patented May 2, 1916.

Application filed November 20, 1915. Serial No. 62,629.

To all whom it may concern:

Be it known that we, WILLIAM ARTHUR WEAVER and WILLIAM THOMAS BROWN, both subjects of the King of Great Britain and 5 Ireland, and residents of Coventry, Warwickshire, England, have invented an Improved Roller-Steady for Lathes and the like, of which the following is a specification.

10 This invention refers to roller steadies as used in lathes and like machines, such as milling or grinding machines, and particularly those combined with a tool holder for cutting and sizing bars, pins, studs and the 15 like, the roller steadies serving to counteract the pressure of the tool on the work.

The invention consists of an improved 20 construction of roller steady wherein the rollers are capable of being adjusted simultaneously and held to the work by a single 25 operating or adjusting device, the chief features of the invention being two independent roller-carrying slides arranged within a casing common to both and each designed 30 to move toward and away from the work, in combination with a screw and cone acting directly upon the slides for causing the rollers to simultaneously approach the work, and a spring for simultaneously drawing 35 both slides and rollers away from the work as the cone is retracted.

A further feature of the invention is an 40 arrangement of lubricating duct and connecting union for conveying a lubricant to 45 the cutting tool while in operation.

Upon the accompanying drawing, Figure 1 illustrates a side exterior elevation (partly 45 in section), and Fig. 2 a sectional plan view of the improved roller steady combined 50 with a tool holder. Fig. 3 illustrates a further side elevation, but with the outer cover or end plate of the roller slide holder removed. Fig. 4 illustrates a transverse sectional elevation of Fig. 3 on line $x-x$. Fig. 5 illustrates a like view to Fig. 3, but with portions of the roller slides removed, and with the fixed central stem of the holder casing in section, the section being taken on line $y-y$, Fig. 4. Fig. 6 illustrates, in perspective, the roller slides separate from their 55 holder. Fig. 7 illustrates a cross section of a modification. Fig. 8 illustrates a side view of a further modification. Fig. 9 illustrates a sectional plan view of Fig. 2.

According to the invention, the improved 55 roller steady comprises a body or base part a , suitable for attachment to the machine in which the roller steady is to be used. In one with such base part is a casing b with detachable side cover plate b' and forming 60 the holder for the roller slides and rollers. The interior of the holder is cylindrical, except at one point, where it is formed with a gap or opening b^2 . This opening lies opposite to the tool holder, which is in one 65 with the base a , and consists of a raised part c formed with a through passage and provided with a set-screw d for the purpose of holding a tool placed in the holder, see Fig. 1. In the rear wall of the casing b 70 and in the cover plate b' is an opening for the work to pass through, the base part a having a part a' in which also is an opening for the work to pass through.

Passing centrally through the casing b is 75 a fixed stud or boss b^3 , the ends of the boss being preferably turned down to fit a hole in the back of the casing and in the cover plate b' , see Fig. 2. Within the annular chamber 80 left between the stud or boss b^3 and the inner cylindrical face of the casing b are arranged the roller slides and rollers. Each slide (see Fig. 6) is made in two parts e' , e^2 , each part being in the form of an approximately 85 flat piece of metal (preferably hardened steel), and the two parts, when placed side by side, being designed to fit within and fill a portion of the annular space within the casing b , see Figs. 3, 4 and 5. At one end each part of each slide is thicker than 90 the other end, see Fig. 4, and at such end the two parts touch each other. Also at the other end of each part and upon each of the opposite faces of the two parts is a stud e^3 , the two studs being in alinement with each 95 other and one touching or almost touching the other, so as to collectively form the axle of a steel roller f placed between the two parts 100 of the slide. For the purpose of affording the necessary clearance between the slides and the work, the ends of the slides are cut away as much as possible, half the diameter of each stud e^3 projecting beyond the edge of the slide, see Fig. 6. For helping to hold the parts e' , e^2 in their proper relative positions, and for causing both to move together 105 while allowing the parts to be separated at any time for the purpose of renewing the

roller f , the part e^2 is provided with a fixed pin g adapted to project loosely through a hole in the part e' , see Figs. 2, 3 and 4. The said pin g extends across the space between the parts of the slide and lies near to the boss or stud b^3 when the slide is in the casing b . By means of a spring h , see Fig. 5, arranged within the said space and secured by its ends to the pin g of one slide and to the pin g of the other slide, the spring serves to draw the slides toward each other. To allow room for the spring, and also to allow the spring to have a more direct pull on the slides, the boss or stud b^3 may be filed away or grooved on the side next the spring, see Fig. 5.

At the rear of the casing b is a bearing b^4 and floating nut b^5 and through such bearing and nut passes a screw i , the forward end of which, within the casing b , is provided with a cone j . This cone, with the rotary and longitudinal movements of the screw, is designed to engage conical or beveled faces on the adjoining ends of the two roller carrying slides, the beveling of the slides extending preferably across the full thickness of the part e^2 and partly across the thickness of the part e' , see Fig. 4. With the screw i fully retracted, the cone j allows the slides to meet or almost meet, and thereby hold the rollers f, f at their furthest distance apart. Upon however, the screw i being screwed into the casing, the cone j causes the slides to separate, and the rollers f, f to approach each other, the movements of the two slides being equal and simultaneous. In this way, with the apparatus in use, and with the bar to be operated upon passing through the casing b , the single regulation of the screw i serves to bring both rollers f, f against the bar, or, with a reverse rotation, to move both away from the bar.

The roller-carrying slides, by being formed to the curve of the casing b and stud b^3 are caused, when operated by the screw i , to move in a curved path, thus insuring the convergence of the rollers on to the work at the proper points. The screw i is provided with a nut k by which the screw, after acting upon the slides to adjust them, may be firmly locked against accidental disturbance.

As an alternative, the screw i may be provided with a cone, the narrow part of which is next the screw, see Fig. 7, the action of the screw then being reversed in operating to separate the slides. In such connection the screw may screw through a floating bush l , this latter, while free to float, being held to the casing b by a flange l' and nut l'' , while the screw is held, after adjustment, by lock nut m .

As a further alternative, (see Fig. 8), a flat-sided wedge n may be used in place of

the cone j , for separating the slides the screw o then being arranged to screw through the cylindrical part of the casing b .

In lieu of forming the roller axles studs in one with the parts e', e^2 of the slides, which is the preferred construction, a pin may be used fixed to or in one with one part and project loosely through a hole in the other part.

For the purpose of supplying oil or the like to the cutting tool, the base a is provided with a duct or passage a^2 which at one end is vertical and opens immediately below the cutting end of the tool, see Fig. 1, while at the other end it is fitted with a supply pipe s . This pipe rises up to a point above the level of the casing b and terminates in a socket or union s' fitted with a flexible packing ring s^2 . By means of this union the operator can readily connect the usual oil supply pipe, the end of the pipe being merely slipped into the socket and the joint being made by the ring s^2 . By supplying the oil upward and on to the point of the tool, see Fig. 9, the speed of cutting may be increased.

What we claim is:—

1. In a combined roller steady and tool holder for lathes and the like, and, in combination, a cylindrical casing, and a supporting base integral with the casing, said base having at one part an opening for a tool and at such part constituting a tool holder, and said base also having a duct or passage for guiding a lubricant upward and on to the point of a tool, when in the holder, and said casing and a vertical part of the base, having an opening for the "work" to pass through, a pair of slides within the casing, a roller carried at one end of each slide, and said slides and rollers movable in paths converging toward or diverging from the "work," means, carried by the casing, for simultaneously advancing the slides and rollers toward and against the "work," and means, inclosed within the casing, for simultaneously withdrawing the slides and rollers from the "work" on the said slide-advancing means being operated to allow of the withdrawal, as set forth. 110

2. In a combined roller steady and tool holder for lathes and the like, and, in combination, a cylindrical casing, and a supporting base integral with the casing, said base having a part extending upward at a short distance from the casing and said casing and the upstanding part of the base having an opening for the "work" to pass through, a pair of slides within the casing, a roller carried at one end of each slide, and said slides and rollers movable in paths converging toward or diverging from the "work," means, carried by the casing, for simultaneously advancing the slides and rollers toward and against the "work," and 120

means, inclosed within the casing, for simultaneously withdrawing the slides and rollers from the "work" on the said slide-advancing means being operated to allow of the withdrawal, as set forth.

3. In a combined roller steady and tool holder for lathes and the like and, in combination, a cylindrical casing, one side of which is fixed and the other removable, a central stud secured to the fixed side of the casing and extending across the interior of the casing, a supporting base integral, with the casing, and said base having a part extending upward at a short distance from the casing, and said casing and the upstanding part of the base each having an opening for the "work" to pass through, a pair of slides within the casing, a roller carried at one end of each slide, and said slides and rollers mov-

able in paths converging toward or diverging from the "work," a screw passing loosely through a hole in the wall of the casing, a loose floating nut within the casing with which the screw engages, a tapered part on the end of the screw adapted simultaneously to engage the slides to separate them, and a spring lying against the said central stud of the casing and at one end engaging one of the slides and at the other end engaging the other slide, as set forth.

In witness whereof we have hereunto set our hands in the presence of two witnesses.

WILLIAM A. WEAVER.
WILLIAM T. BROWN.
